(57) **CLAIM**

The ornamental design for a pulsating electromagnetic field generator, as shown and described.

DESCRIPTION

FIG. 1 is a top front perspective view of a pulsating electromagnetic field generator showing my new design; FIG. 2 is a bottom front perspective view thereof; FIG. 3 is a top rear perspective view thereof; FIG. 4 is a bottom rear perspective view thereof; FIG. 5 is a front view thereof; FIG. 6 is a rear view thereof; FIG. 7 is a top view thereof; FIG. 8 is a bottom view thereof; FIG. 9 is a right side view thereof; and, FIG. 10 is a left side view thereof.

The broken line showing not-claimed items illustrated in figures; i.e. segments of wall surfaces between each corner of the pulsating electromagnetic field generator in FIG. 1 through FIG. 10, a plurality of light indicators in FIG. 1 through FIG. 2 and in FIG. 6, and a port for an electrical power outlet in FIG. 4 and in FIG. 7; is included for the purpose of illustrating environmental structure and forms no part of the claimed design.
